[57] CLAIM

The ornamental design for a modular terminal board, as
shown and described.

DESCRIPTION

FIG. 1 is a front and upper right perspective view of a
modular terminal board showing my new design. The
broken line showing is included for the purposes of
illustrating environmental elements only and forms no
part of the claimed design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.
